AUTOMATIC VOLUME CONTROL

Harry Bricker Fuchs, Brooklyn, N. Y.

Application October 20, 1937, Serial No. 170,049

8 Claims. (Cl. 250—20)

My invention relates to an electrical device, method and system and apparatus for the local and distant control of devices of various kinds, as for example wireless tuning mechanisms.

5 One object of this invention is to provide a simple, inexpensive, and efficient low speed motor adapted to impart movement to devices by a series of rapid pulses.

Another object of this invention is to provide 10 an exceptionally simple and low priced motor for light work, as for instance operating communication devices, time switches, animated display and advertising devices, toys, valves, apparatus and machines of various kinds, acoustic 15 and optical signalling installations, firing equipment for blasting, etc.

Another object of the invention is to provide a simple device sufficiently low in cost so that it can be used to control low-priced wireless sets, 20 thereby performing a public service by making it possible for the average public to enjoy greater radio operating comfort by purchasing low-priced wireless sets embodying this invention.

A further object of this invention is to provide 25 an apparatus and method whereby the actuation of a single control means will operate the tuning element of a wireless set and automatically operate the volume control of the wireless set in response to the tuning element reaching a 30 predetermined position until the listener hears the desired volume and stops the actuation of the single control means therat.

Still further objects of this invention will appear hereinafter.

35 This invention accordingly consists in the method, system, combinations of elements, arrangement of parts, and in the several steps and relation and order of each of the same to one or more of the others as will be disclosed herein.

40 The many novel features embraced in this invention are far-reaching in their scope and are applicable in many embodiments other than that described, and I therefore do not wish to be limited except as indicated in the appended claims.

45 In the drawing Figure 1 is a diagrammatical view of one embodiment of the invention, and Figure 2 is a perspective view clearly illustrating the new, novel and very simple manner in which the shaft is rotated.

50 Referring to the drawing, 1 indicates the base of electrical insulating material to which is secured the electromagnets 2 and 3 having core extensions 4 and 5. The armature 6 having a contact point 7 and the armature 8 having a contact point 9 are loosely mounted on the shaft 10

which may be connected with the rotor shaft of a wireless tuning condenser by means of an electric insulating coupling so that shaft 10 is electrically insulated therefrom. 11 and 12 indicate strands made of material that yields under stress and returns to its normal form when the stress is removed, such for instance as metal spring wire or a springy non-metallic material as for instance rattan. These strands may be covered with a friction material, as for example rubber. These 10 strands and the method of using them are a very important part of the invention, and as clearly illustrated in Figure 2 the strand 11 or 12 is loosely coiled around shaft 10, one end thereof being braced against or secured to the armature 15 6 or 8 and the other end terminating in a loop. As shown in Figure 1, these loops are tensioned 20 against the end of screw 13 positioned in post 14 and against the end of screw 15 positioned in post 16, and the adjustment of these screws by 20 a screw-driver inserted through holes in core extensions 4 and 5 determines the proper looseness of the coiled strands 11 and 12 on shaft 10 so that when either armature 6 or 8 is vibrated by its respective electromagnet 2 or 3, each time either 25 armature is attracted by its electromagnet it tightens its coiled strand upon the shaft 10 and causes the shaft to rotate a small distance in a direction. It will thus be seen that when one end of a strand is secured in a fixed position the 30 movement of the other end of the strand in an arc toward the fixed end will tighten the coil of the strand on the shaft and thereby rotate the shaft a small distance.

The contact spring 17 secured to post 18 normally contacts with contact point 7, and the contact spring 19 secured to post 20 normally contacts with contact point 9. 21 indicates multiple closely spaced holes, in base 1, having contact pins 22 inserted therein in various spaced 40 relationship in accordance with predetermined points, such for instance as the resonance points of a wireless tuning condenser. Each contact pin is connected by means of a flexible cable 23 to a post or lug 24 secured in base 1, of which only a few are shown for purpose of clearness, with the understanding that any number of posts or lugs 24 and the flexible cables and contact pins connected thereto may be used. 25 indicates 45 carrier means, as for instance wires, connected from posts or lugs 24 to the locally or remotely positioned current switching members 26. Each pair of current switching members 26 and 27 are adapted to be actuated simultaneously and 50 55

therefore both may be secured to a piece of electric insulating material.

28 indicates a switch arm secured to shaft 10 and adapted to contact the ends of contact pins 22 on the back side of base 1 during the rotation of shaft 10. 29 indicates switching means, positioned on the back side of base 1, consisting of a strip of electric insulating material loosely mounted on shaft 10 and having offsets 30 at each end thereof adapted to be struck by switch arm 28 when the switch arm is at an extremity of its range. One end of switching means 29 carries a metal lug adapted to bridge the circuit between contacts 31 and the other end of switching means 29 carries a metal lug adapted to bridge the circuit between contacts 32, so that when switch arm 28 strikes offset 30 at one extremity of its range one lug bridges contacts 31, as shown, and when switch arm 28 strikes the other offset 30 at the other extremity of its range it opens the circuit between contacts 31 and bridges the circuit between contacts 32. The use of the metal lugs at the ends of switching means 29 are easily understood by those skilled in the art and therefore they are not shown in the drawing for purpose of clearness.

In operation, each contact pin 22 is inserted in a hole 21 at a predetermined position in accordance with the resonance point of a wireless station, and when one pair of switching members 26 and 21 is actuated, as for example the pair at the extreme left in the drawing, current from line 33 passes through shaft 10, armature 6, contact point 7, contact spring 17, post 18, line 34, contacts 31, line 35, electromagnet 2, lines 36 and 37, switching member 27, contact 38 to line 39. Electromagnet 2, now being energized, core extension 4 attracts armature 6 so that the coiled strand 11 tightens on shaft 10 and moves the shaft a small distance in the clockwise direction, and the interruption of the flow of current by the movement of armature 6 away from contact spring 17 causes deenergization of electromagnet 2, whereupon the end of strand 11 tensions armature 6 against contact spring 17 and energizes electromagnet 2 whereby core extension 4 again attracts armature 6, so that the whole operation is repeated and the vibration of armature 6 will cause the coiled strand 11 to intermittently grip shaft 10 and move it in a clockwise direction until the flow of current is stopped.

As previously noted, the actuation of the pair of switching members 26 and 27 at the extreme left in the drawing is causing the rotation of shaft 10 in a clockwise direction and when switch arm 28 contacts the contact pin connected to switching member 26, as shown in Figure 1, current from line 33 passes through shaft 10, switch arm 28, contact pin 22, flexible cable 23, post or lug 24, line 25, switching member 26, contact 40, line 41, motor device 42, line 43 to line 39. The motor device 42 is now energized and operates the volume control 44 of a wireless set. However, motor device 42 is of lower resistance than electromagnet 2 so that the current flows through the path of least resistance which is motor device 42 and electromagnet 2 does not operate because of insufficient current. The motor device 42 is now operating volume control 44 from minimum to maximum or vice versa until the listener hears the desired volume and stops the operation of motor device 42 thereat by releasing the switching means 27 and 26 from contact with contacts 38 and 40.

In other words, when a pair of switching members are actuated, an electromagnet vibrates an armature which moves the shaft in a direction, and when the switch arm secured to the shaft contacts a contact pin which has been preset in a hole in the base in accordance with the resonance point of a wireless station and is connected to one of the actuated switching members, then the motor device connected to the other actuated switching member short-circuits and thereby stops the operation of the electromagnet and at the same time operates a volume control until the listener hears the desired volume and disengages the switching members thereat. In this manner the single motion of actuating both switching members simultaneously automatically stops a wireless tuning element at a predetermined point and then automatically varies a volume control until the listener stops the actuation of the switching members upon hearing the desired volume produced by the speaker of the wireless set. 5 10 15 20

It will of course be understood that instead of being connected to the motor device 42, lines 41 and 43 may be connected to a relay for stopping the actuation of the wireless tuning element, or to switching means for energizing or deenergizing electroresponsive devices in response to the tuning element reaching predetermined positions. 30

It will be further understood that the electromagnets used for actuating the armatures are merely one example and that other electroresponsive devices, through which passes the current by which they are actuated or operated, 36 may be used.

It is not necessary to give a detailed description of the circuit including electromagnet 3 which is operative in the same manner as the circuit including electromagnet 2, with the exception that when shaft 10 is not stopped by the contact of switch arm 28 with a contact pin 22 connected to an actuated switching member, the continued movement of switch arm 28 in a clockwise direction will cause it to strike offset 30 and so cause the metal lug in switching means 29 to bridge contacts 32 thereby deenergizing electromagnet 2 and energizing electromagnet 3 to actuate armature 8 to move shaft 10 in an anti-clockwise direction. In other words, when switch arm 28 reaches an extremity of its range it actuates switching means 29 which deenergizes the operating electromagnet and energizes the other electromagnet to move shaft 10 in an opposite direction, so that each time switch arm 28 reaches an extremity of its range shaft 10 is automatically rotated in the opposite direction.

Although one form of the invention has been illustrated and described, it will be obvious that my invention may take several forms and therefore I do not wish to be limited except as set forth in the appended claims.

I claim:

1. An electrical device comprising a tuning element, a single control adapted to be moved in a direction for controlling the adjustment of the tuning element to a desired point of resonance, a contact element at the desired point of resonance connected with the single control, a volume control adapted to be varied between minimum and maximum, and a motor device connected to the contact element adapted to vary the volume control when the tuning element is at a desired point of resonance, the motor device adapted to be stopped at the desired degree of 65 70 75

volume by the movement of the single control in another direction.

2. An electrical device comprising a tuning element, means for adjusting the tuning element to a desired point of resonance, a contact element at the desired point of resonance, a volume control adapted to be varied, an electroresponsive device connected with the contact element adapted to vary the volume control when the tuning element is at the desired point of resonance, and a single control connected with the contact element adapted to be actuated for controlling the adjustment of the tuning element to the desired point of resonance and to be released to stop the operation of the electroresponsive device at the desired degree of volume.

3. An electrical device comprising a tuning element, an arm moving with the tuning element, a preset contact element, a volume control adapted to be varied between minimum and maximum, an electroresponsive device for varying the volume control adapted to be energized by the engagement of the arm with the preset contact element, and manually operable means for stopping the varying of the volume control.

4. An electrical device comprising a first movable member associated with a tuning element, a second member pre-set in accordance with the resonance point of a communications station, a motor device for operating a volume control, and means responsive to movement of the first member into engagement with the second member to actuate the motor device.

5. An electrical device comprising a first member associated with a tuning element, a second member preset in accordance with the resonance point of a communications station, a motor de-

vice for operating a volume control, means responsive to movement of the first member into engagement with the second member to actuate the motor device, and manual means for stopping the motor device.

6. An electrical device comprising two switching members adapted to be actuated simultaneously, a tuning element, an electroresponsive device for actuating the tuning element connected with one switching member and a motor device for varying a volume control connected with the other switching member, a first member associated with the tuning element, a second member preset in accordance with the resonance point of a communications station, and means responsive to movement of the first member into engagement with the second member to actuate the motor device.

7. An electrical device comprising a tuning element, an arm moving with the tuning element, a contact element pre-set in accordance with the resonance point of a station, a volume control adapted to be varied between minimum and maximum, and a motor device for varying the volume control adapted to be energized by the engagement of the arm with the contact element.

8. An electrical device comprising a tuning element, a switching member controlling the adjustment of the tuning element to a desired point of resonance, a contact element at the desired point of resonance connected with the switching member, a volume control adapted to be varied between minimum and maximum, and a motor device connected to the contact element adapted to vary the volume control when the tuning element is at the desired point of resonance.
